UNITED STATES PATENT OFFICE.

EMIEL F. KLINGLER, OF AMERY, WISCONSIN.

WINDOW SILL.

Application filed April 6, 1923. Serial No. 630,382.

To all whom it may concern:

Be it known that I, EMIEL F. KLINGLER, a citizen of the United States of America, residing at Amery, in the county of Polk and State of Wisconsin, have invented certain new and useful Improvements in Window Sills; and I do hereby declare that the following is a full, clear, concise, and exact description of the invention, such as will enable others skilled in the art to which it appertains to make and use the same.

This invention relates to improvements in window sills, having for an object to provide a window sill of such construction as will permit the building or constructing of a weather-tight window whereby the admittance of rain or wind, or other elements into a room of a building so equipped will be prevented, and the positive fitting of the sash in the frame to prevent rattling and air spaces will be effected.

It is likewise an object of the invention to provide a window sill having means thereon for permitting the positive and weather-tight engagement of the same with a plaster wall and weather boarding.

Yet another object of the invention is to provide a window sill whose construction is such as will permit of its use with any form of stock window frame without additional costs.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

40 In these drawings:—

Figure 1 is a vertical transverse section through a window sill constructed in accordance with my invention showing the relative arrangement of the lower sash and the window frame with relation thereto;

Figure 2 is a fragmentary elevation showing the manner in which the sill is fitted to the sides of a window frame;

Figure 3 is a fragmentary detail in top plan of the improved sill; and,

Figure 4 is an end elevation of the same.

Having more particular reference to the drawings, in connection with which like characters of reference will designate corresponding parts throughout, the improved sill is adapted to be used in connection with

any form of stock window frame which is indicated in its entirety by the numeral 1, said frame, of course, including the usual inside stops 2, inside casing 3, and blind stops 4; vertical ways 5 being formed in the inner sides of the frame whereby to slidably receive the upper and lower sashes, the lower sash being shown herein and indicated by the numeral 6. The window is also provided with the usual inside window stool 7 as well as an inside window apron 8, the latter having its upper end arranged adjacent the inner end of the window sill as indicated in the Figure 1, while the lower portion thereof is engaged with the inner side of the plaster wall, hereinafter more fully described.

A stud 9 is arranged directly below the lower portion of the frame 1 and serves as a supporting and spacing element; a plaster wall 10 having laths 11 embedded therein being arranged adjacent one end of said stud and overlapped by the inside window apron 8, while sheathing 12 is arranged adjacent the opposite end of said stud and receives the usual weather boarding 13 thereon.

The improved window sill may be stated to comprise a body indicated in its entirety by the numeral 14 formed of wood or other material and having a longitudinally disposed shoulder 15 formed upon the upper side of its inner portion as shown in the Figure 1; said shoulder being bevelled as at 16 adjacent or at its point of jointure with the corresponding side of the sill body, while a second and right angularly formed shoulder 17 is formed in the upper side of said window sill in proximity to the outer portion thereof and serves as an effectual weather check for the swinging storm sash 18 suitably mounted upon the window frame. In this connection, it is to be noted that the lower marginal portion of the storm sash 18 is dressed sufficiently to provide for ample clearance as between it and the adjacent side of the window sill whereby free swinging movement thereof may be had. However, when the sash is swung to its closed position, the inner portion of the lower end thereof will abut the right angularly formed shoulder 17 and thus provide an effectual weather check whereby to prevent the passage of the elements thereby. The opposite end portions of the upper side of the sill body 14 are cut away, recessed, or

grooved as indicated at 19 in order that the sill may be fitted to the lower end of the opposite sides of the window frame 1 in the usual manner and without extra costs. 5 Hence, it will be understood that the improved window sill may be successfully used in connection with any form of stock window frame now employed in building.

The under side of the sill 14 is rabbeted 10 adjacent its inner portion as indicated at 20 in the Figure 1 and into this pocket or rabbeted portion, there is snugly fitted the upper end of the plaster wall 10. This groove or way formed in the sill is sufficiently deep to permit of the reception of the upper portion of one of the laths 11 therein and the nailing or securing of the same to the sill whereby to provide a positive connection therebetween as well as to provide 15 ample space for reception of the plaster and avoid the shrinking or cracking of the plaster away from the sill with the resultant forming of voids through which cold air, rain or the like may pass. Also, in the 20 under side of the sill 14 in proximity to the outer portion thereof, there is formed a longitudinally extending groove or pocket 21 adapted to receive the upper portion of the weather boarding 13 and thus provide 25 an effectual weather check therefor in order that the passage of the elements between the weather boarding and the adjacent portion of the sill 14 will be prevented.

From the foregoing, it will be understood 30 by workers skilled in the art that I have provided a simple but highly efficient form of window sill, embracing effectual weather checks whereby the passage of wind or rain thereby into the rooms of a building so equipped will be positively prevented and furthermore, whereby a positive and firm connection may be established between the window sill and the plaster wall, thus lending 35 to the general stability of the construction. Also, it will be understood that in fitting the bottom sash 6 to the improved window sill, a portion of the lower end thereof will be bevelled to correspond to the bevelled portion 16 of the shoulder 15 and hence, when said sash 6 is moved to its 40 lowermost position and engages the bevelled portion 16, the same will be caused to be moved laterally into positive connection with the parting stop 22, thus lending to the weather-tight connection or arrangement of the lower sash in the window frame as well as preventing the objectionable rattling of the sash in the frame when subjected to wind pressure.

60 Because of the arrangement of the shoulder 15 and its bevelled jointure 16 with the upper side of the window sill 14, it is to be

understood that the passage of rain or other ones of the elements between or by the sash 6 and said portion of the window sill will be prevented and thus, a highly effectual form of weather check will be provided at this point. The same is true as of the engagement of the lower end of the storm sash 18 with the 65 right angularly formed shoulder 17 of the window sill 14, this arrangement likewise preventing the passage of wind or rain by the storm sash and the adjacent portion of the window sill. Furthermore, as previously set out herein, the engagement of the rabbeted inner end or portion 20 of the sill with the plaster 10 is such as to provide a positive and effectual weather check and also, to prevent the shrinkage or movement of the wall from the window sill or vice versa, and likewise, the engagement of the weather boarding 13 in the pocket 21 formed in the under side of the outer portion of the sill 14 provides a further positive 70 80 85 weather check.

Manifestly, the construction shown is capable of considerable modification and such modification as is within the scope of my claim, I consider within the spirit of my invention.

I claim:—

A window sill comprising a single piece of material having the opposite end portions of its upper and lower faces formed in parallel relationship, an upstanding portion formed upon the upper face of said piece of material disposed longitudinally thereof and having its ends terminating inwardly of the opposite ends of said piece of material and one side thereof terminating inwardly of the corresponding side of said piece of material while its opposite sides terminate flush to the corresponding side of the piece of material, said upstanding portion being provided upon one side thereof and adjacent that end of the same flush with the corresponding side of said piece of material with a longitudinally disposed shoulder having a plane bevelled portion joining with said upstanding portion, the jointure of the inwardly spaced sides of said upstanding portion with the piece of material inwardly of the corresponding side thereof forming another longitudinally disposed and right angularly formed shoulder, and the lower face of said piece of material having portions thereof longitudinally grooved and rabbeted, as and for the purpose set forth.

In witness whereof I have hereunto set my hand.

EMIEL F. KLINGLER.
